232,270

COMBINED CARRYING CASE AND TENNIS RACKET HOLDER

Samuel N. Glantz and Milton Glantz, both of 1127 W.
Division, Chicago, Ill. 60622

Filed Sept. 18, 1972, Ser. No. 290,238

Term of patent 14 years

Int. Cl. D3—02
U.S. Cl. D87—1 R

FIG. 1 is a front perspective view of a combined carrying case and tennis racket holder showing our new design;

FIG. 2 is a rear elevational view;

FIG. 3 is a top plan view;

FIG. 4 is a bottom plan view;

FIG. 5 is an elevational view looking from the left of FIG. 2; and

FIG. 6 is an elevational view looking from the right of FIG. 2.

We claim:

The ornamental design for a combined carrying case and tennis racket holder, as shown.
